DIGESTER

Augustus C. Durdin, Jr., Chicago, Ill., assignor
to Chicago Pump Company, Chicago, Ill., a
corporation of Illinois

Application November 29, 1937, Serial No. 177,082

8 Claims. (Cl. 210—2)

This invention relates to digesters and particularly to digesters in which the decomposition of sewage, sludge, and other organic materials is conducted under anaerobic conditions.

Organic decomposition of this type is accompanied by the evolution of gas of considerable calorific value. This gas is normally burned for useful purposes and usually at least some of the heat derived therefrom is utilized for the heating of the material being decomposed, since the decomposition is considerably accelerated by reasonably high temperature, of the order of 90° or 100° F.

In digestion as heretofore practiced, considerable difficulty has been experienced by the formation of a solid cake or crust within the digester, particularly in the zone of the liquid level. It is believed that the gas produced in the process carries solid materials upwardly and causes them to float and these floating solid materials for some reason or other tend to agglomerate at the surface of the liquid and to coalesce on the apparatus at that level.

One of the principal objects of the invention is to provide apparatus in which the formation of a crust in excessive amounts is prevented.

A further object of the invention is to provide improved means for storing a certain amount of gas in the digester and for utilizing said storage means for maintaining the solids submerged against any tendency to float.

The invention will readily be understood from the following description of a preferred embodiment thereof, taken in conjunction with the accompanying drawing which is a vertical sectional view through a digester embodying my invention.

The digester comprises a basin 10 which may suitably be built of concrete. This basin may be round, square, or of other suitable shape in cross-section. It is preferably relatively deep and is provided with a hopper bottom 11. At its lowermost point the tank is provided with an outlet pipe 12 controlled by a valve 13, so that the mud-like precipitate resulting from the decomposition position may be drawn off at will.

Within the tank 10 is a heating coil 14 through which circulates any suitable medium heated by the combustion of some or all of the gas produced by the digester, in well-known manner. The tank 10 is provided with an inlet 15 which is provided with a valve 16, whereby the admission of sludge, sewage, or other materials which are to be decomposed, may be controlled. A gas-holding bell 17 is located in the upper part of the tank 10. This bell may have a flat upper

wall 18 and a vertical wall 19 depending therefrom, which wall closely conforms in shape to the shape of the tank 10. The wall 19 is somewhat smaller than the interior outline of the tank 10 so that the bell 17 may move freely within the tank. 5

An impervious conduit or pipe 20 extends from a position a short distance below the upper wall of the gas bell 17 and extends downwardly in a vertical direction to a point somewhat above the lower edge of the gas bell. The pipe 20 is supported from the upper wall 18 of the gas bell 17 by means of brackets 21. At a level a short distance above the lower end of the pipe 20 I provide a horizontal perforate wall 22 which extends 15 from the pipe 20 to the skirt or vertical wall 19 of the bell 17. This perforate wall is mounted in position by being secured to the pipe 20 and the vertical wall 19. It may suitably consist of a woven screen of suitable mesh to prevent any 20 but the smallest solids from passing through. Thus, I may employ a wire screen of $\frac{1}{8}$ " mesh or finer screen, such as $\frac{1}{2}$ " or $\frac{1}{16}$ " mesh, or a screen of even finer mesh. In some cases, however, I prefer to employ a grille or screen having 25 a larger opening size or mesh.

A gas outlet pipe 23 extends into a tank 10 and terminates in an upwardly directed vertical length 24 which projects freely through the pipe 20 to a point above the normal surface level of the liquid which is defined by an overflow pipe 25 which extends from an intermediate position on the tank 10 at a place remote from the inlet 15. The overflow pipe 25 extends upwardly to a lead-off pipe 26 located at the desired liquid 35 level of the tank. Stops 27, suitably projecting from the wall of the tank 10, prevent excessive movement of the bell 17 into the tank 10.

The operation is as follows: The material to be digested is introduced by the inlet 15 so as to 40 fill the tank up to the level defined by the outlet pipe 25, 26. The valve controlling the pipe 23 is opened so as to allow substantially all the air in the bell 17 to escape and to allow the liquid to enter into the bell to the liquid level, through 45 the perforated partition 22. It is to be noted that the perforated partition 22 prevents solid material from rising into the upper part of the bell and these solid materials are therefore maintained submerged at all times. Heated medium 50 is passed through the coil 14 and the liquid is brought to a suitable digesting temperature.

The decomposing material produces gas which rises upwardly through the screen 22 and collects in the bell 17. Some of this gas forms in solid 55

materials and floats them into contact with the perforated wall 22. Owing to the foraminous nature of the wall 22, the gas is allowed to free itself from the solid materials and pass upwardly into the upper part of the bell 17. When solid materials are freed from gas in this way, they sink downwardly and tend to disintegrate. As the gas accumulates in the bell 17, the bell rises and in normal operation the gas is drawn off by the pipe 23 at sufficient rate to maintain the bell 17 at an intermediate position floating on the liquid in the tank 10.

The varying positions of the bell 17 relative to the level of the liquid causes flow of the liquid in both directions through the perforated wall or screen 22 and this current effectively cleans the wall or screen 22 and prevents it from becoming choked.

In the event that the perforated wall or screen 22 does become choked to some extent, the gas produced will accumulate beneath this wall owing to the projection of the tube 20 below the wall, and consequently the liquid above the wall will flow down through partially choked openings in the wall 22 and will remove material from these openings. In any event, the bell 17 floating freely on the liquid in the tank 10 and being unsecured in any way, it may readily be removed, the screen or wall 22 cleaned, whereupon the bell 30 may be reinstalled.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

40 1. A digester comprising a basin, an inverted gas bell adapted to float in the upper part of said basin, and a foraminous wall mounted on, and extending across said bell adapted normally to be submerged in the liquid therein, said wall being adapted to maintain normal sludge solids submerged.

45 2. A digester comprising a basin, an inverted gas bell adapted to float in said basin, and a foraminous wall carried by and extending across the interior of the lower portion of said bell, said wall being adapted to maintain normal sludge solids submerged.

50 3. A digester comprising a basin, an inverted gas bell adapted to float in said basin, a conduit within the bell extending from the lower portion of the bell to a point slightly below the upper end

of the bell, and a foraminous wall mounted on the bell within the lower part of the bell and extending between said bell and said conduit, said wall being adapted to maintain normal sludge solids submerged.

5 4. A digester comprising a basin, an inverted gas bell adapted to float in said basin, a conduit within the bell extending from a point above the lower edge of the bell to a point slightly below the upper end of the bell, and a foraminous wall 10 mounted on the bell within the lower part of the bell and extending between said bell and the conduit at a position above the lower end of said conduit, said wall being adapted to maintain normal sludge solids submerged.

15 5. In a digester, in combination, a basin, a foraminous wall therein adapted to be submerged in normal operation, means below said wall for introducing liquid to be digested, means above said wall for collecting gases produced in said basin, said wall being adapted to maintain normal sludge solids submerged, and means actuated by said gases for varying the position of said foraminous wall in the basin.

20 6. The method of digesting liquid containing organic materials which consists in maintaining a body of liquid under digesting and gas forming conditions, arresting solid materials tending to float owing to gas adherence and maintaining them submerged by a submerged screen while maintaining free degassing conditions to enable the solid material to be degassed and caused to sink, maintaining said screen submerged in the liquid, and varying the level of said screen whereby liquid flows therethrough.

25 7. In a method of digesting, in combination, maintaining liquid containing organic materials under digesting and gas forming conditions, arresting solid materials and maintaining them submerged by a submerged screen, maintaining free passage for gas above said solid materials whereby gas may separate therefrom and move upwardly, maintaining said screen submerged in the liquid, collecting said gas, and displacing liquid through said screen by said gas.

30 8. In a method of digesting, in combination, maintaining liquid containing organic materials under digesting and gas forming conditions, arresting solid materials and maintaining them submerged, maintaining free passage for gas above said solid materials whereby gas may separate therefrom and move upwardly, causing liquid to flow past said submerged solid materials in both directions, and moving said arrested solid materials to various levels in the liquid.

AUGUSTUS C. DURDIN, JR.
